RAIL FLAW DETECTOR MECHANISM

Harcourt C. Drake, Hempstead, and George L. Jones, Garden City, N. Y., assignors to Sperry Products, Inc., Brooklyn, N. Y., a corporation of New York

Application April 22, 1932, Serial No. 606,808

8 Claims. (Cl. 175—183)

This invention relates to rail flaw detector mechanisms of the type employed in the Sperry rail flaw detector car. In said mechanism, the current is generated within the car and supplied to sets of brushes which lead the current into and out of the rail to establish an electromagnetic field surrounding the rail. Sets of induction coils are then moved along the rail through the electromagnetic field cutting the lines of force to generate an E. M. F. The coils are arranged in opposite pairs so that when both coils are cutting the same number of lines of force no differential E. M. F. is generated but when a region of flaw is encountered, the coils being arranged in tandem, one coil will cut a different number of lines of force from the other coil to generate a differential E. M. F. The current brushes are carried by a current brush carriage suspended from the car body and the induction coils are carried by a detector carriage suspended from the current brush carriage. In the forms of detector mechanism which are here illustrated, the coils are carried in metallic casings which engage the rail. The current brush carriage and the detector carriage are also of metal, which are therefore electrical conductors.

Because of the construction described above, it has been found that in some instances false indications as of a flaw were obtained where no flaw existed, and this was traced to the fact that since the current brush carriage, detector carriage, and the casings for the induction coils were all of conductive material, electric circuits and condenser effects were established in these various parts because they engaged the rail through which current was passing. Such circuits and condensers were, of course, of variable characteristics, and the variations in flux thus set up by these factors were picked up by the induction coils in the same manner as a flaw.

It is the principal object of our invention, therefore, to make provision in the flaw detector system hereinbefore described for preventing setting up such stray electric circuits and the establishment of condensers whose variable characteristics may possibly induce flux in the induction coils.

Further objects and advantages of our invention will become apparent in the following detailed description thereof.

50 In the accompanying drawing,

Fig. 1 is a side elevation of a portion of a Sperry rail flaw detector car showing one form of our invention applied thereto.

55 Fig. 2 is an enlarged view of the search unit shown in the Fig. 1 form of the invention.

Fig. 3 is a section taken on the line 3—3 of Fig. 2.

Fig. 4 is a side elevation of a modified form of detector unit having our invention applied thereto.

Fig. 5 is a plan view, partly sectioned, of a detail of one of the induction coil mountings of Fig. 4 showing our invention applied thereto.

Referring to Fig. 1 of the drawing, there is disclosed a portion of a Sperry rail flaw detector 10 from which is suspended the detector mechanism by means of pistons 11 and retracting cables 12. The pistons 11 operate in fluid pressure cylinders 13 whereby the detector mechanism may be lowered against the action of the 15 retracting mechanism. Current is supplied to the rail from a generator G within the car-body to sets of current brushes 15 and 16 carried by a current brush carriage 17. The said sets of brushes are in engagement with the rail and lead current 20 into and out of the same to establish an electromagnetic field surrounding the rail. The current brush carriage travels along the rail on any suitable means, such as wheels 14. Flaws are detected by means of a search unit 20 which is supported on a detector carriage 21 which is in turn supported on the current brush carriage 17. The detector carriage 21 may ride upon the rails on means such as wheels 22. In the form of search unit shown, the induction coils are mounted with 25 in cylinders 23, said cylinders being of metal adapted to ride upon the rail. The axes of the coils are equidistant from the rail so that as the car travels along the rail the coils cut an equal 30 number of lines of force. Since the coils are 35 connected in opposition no E. M. F. is generated until a region of flaw is encountered which displaces the electromagnetic field so that on entering said field one coil cuts more or less lines of 40 force than the other to induce an E. M. F.

Referring to Fig. 2, it will be seen that the metallic casings 23 enclosing the induction coils are mounted in the frame 20' which is supported on the detector carriage 21 by metallic bolts 25. The detector carriage 21 is itself of conductive material and is supported on the current brush carriage by means such as metallic bolts 26. The current brush carriage 17 is likewise of conductive material. It will now be seen that since current of large amperage is flowing through 50 the rail, if the frame 20' were also of conductive material there would be ready opportunity for the establishment of local electric circuits from the rail through the casings 23 and thus by various paths through casing 21 to wheels 22 or 55

through casing 21 and casing 17 to wheels 18 and back to the rail, since all of said parts are of conductive material. Since the casings 23 are of metallic material and the coils are formed by 5 wires which are encased in insulation, condensers are established with the covering of the wires forming the insulation between two conductors. It is further apparent that these local circuits and this condenser effect is not constant but would 10 vary with many factors, and such variations would cause a changing flux which would affect the induction coils to generate an E. M. F. which would give a false indication as of a flaw.

We obviate this condition and prevent the 15 establishment of such local electric circuits and condenser effects by the following means: The frame 20' in which the casings 23 are mounted and by which the coils are supported on the detector carriage, and hence on the current brush 20 carriage, is formed of an insulating material such as Bakelite which effectively prevents the establishment of any of the local electric circuits mentioned above, as will be seen from Fig. 3, because any such circuit extending from the casings 23 25 is effectively interrupted by the insulating frame 20'. Similarly, the condenser effect within the casings is prevented since there is no outlet for the discharge of such condenser, the coils not being grounded since they are supported in the 30 insulating frame 20'. Further prevention of the establishment of local electric circuits and condenser effects is obtained by insulating the brushes 15 and 16 and the lower portion 17' of the carriage 17 which supports said brushes from the upper portion 17" of said carriage by means 35 of insulation 18.

The principle disclosed above for eliminating flaws due to the establishment of local circuits and condenser effects may be applied, also to 40 another form of Sperry detector unit. In this form of detector unit each coil 24 is mounted within a casing 23' which is individually supported for movement within the detector carriage 21' upon a frame 30 pivoted in said carriage at 31. The details of this mounting are disclosed in Fig. 5 wherein it is seen that the frame 30 is fixed to a stub shaft 31 journaled in the side walls 32 of the detector carriage. Each casing 23' is pressed into engagement with the rail 45 by means such as a hairpin spring 35 surrounding the shaft 31 and anchored at one end against a fixed bolt 36 in the walls 32 of the detector carriage and pressing with its other end upon the arm 30. The detector carriage is supported from the current brush carriage by means such as bolts 26 and springs 40, said carriage being in engagement with the rail by means such as rollers 42.

It has been seen that the same condition exists in the Fig. 4 form of the invention as in the 60 Fig. 1 form, namely, that unless provision were made to prevent the establishment of local electric circuits and condenser effects such circuits could be established through casings 23', arms 30, shafts 31, walls 32, wheels 42 and the rail, 65 while condenser effects could be established within the casing 23' between the casing and the coil 24, the wrapping around the coils acting as a di-electric. We, therefore, make provision for preventing the establishment of such local circuits and condenser effects so that the variations in these factors will not be able to generate E. M. F.'s within the coils. For this purpose we prevent the establishment of local circuits by providing Bakelite bearings 50 between the shafts 31 (which carry arms 30) and the

casings 23' on the one hand, and the walls 32 of the detector carriage on the other. Said insulating bearings 50 are provided with flanges 51 to complete the insulation between the hubs 52 of arms 30 and the side walls 32 of the carriage. There is still another path through which such circuits may be established, said path being by way of arms 30, or springs 35, and the fixed bolt 36. Therefore, we provide insulating bearings such as Bakelite bearings 55 between the fixed 10 bolt 36 and the side walls 32 of the detector carriage.

For preventing the establishment of condenser effects within the casing 23' we have shown the 15 end wall 21 of the said casing as being formed of insulating material, such as Bakelite. The coil 24 is supported out of contact with the walls of casing 23' by means of insulating brackets 28 fixed to the end wall 21. By this construction there is no path by which the condenser may 20 discharge.

In accordance with the provisions of the patent statutes, we have herein described the principle and operation of our invention, together 25 with the apparatus which we now consider to represent the best embodiment thereof, but we desire to have it understood that the apparatus shown is only illustrative and that the invention can be carried out by other means. Also, while 30 it is designed to use the various features and elements in the combination and relations described, some of these may be altered and others omitted without interfering with the more general results outlined, and the invention extends 35 to such use.

Having described our invention, what we claim and desire to secure by Letters Patent is:

1. In a flaw detector mechanism for rails and the like, said mechanism being adapted to move along the rails, in combination, a source of current, means for supplying said current to the rail including a current brush carriage, said carriage comprising a frame having wheels engaging the rail and sets of current brushes for leading current into and out of the rail, means supported by said carriage and responsive to variations in flux around the rail for detecting flaws therein, and means for insulating from said wheels and brushes the portion of said carriage frame which supports said responsive means.

2. In a flaw detector mechanism for rails and the like, said mechanism being adapted to move along the rails, in combination, a source of current, means for supplying said current to the rail, means responsive to variations in flux around the rail for detecting flaws therein, said last-named means comprising an induction coil, a conductive casing therefore adapted to engage the rail, a support for said casing on said carriage, and means for insulating said casing from said carriage.

3. In a flaw detector mechanism for rails and the like, said mechanism being adapted to move along the rails, in combination, a source of current, means for supplying said current to the rail, means responsive to variations in flux around the rail for detecting flaws therein, said last-named means comprising a plurality of induction coils, a conductive casing for each of said coils and an insulating support for said casings.

4. In a flaw detector mechanism for rails and the like, said mechanism being adapted to move

- along the rails, in combination, a source of current, means for supplying said current to the rail, means responsive to variations in flux around the rail for detecting flaws therein, said last-named means comprising a plurality of induction coils, a conductive casing for each of said coils, means whereby said carriage supports said casings, and means whereby said casings are insulated from said carriage.
5. In a flaw detector mechanism for rails and the like, said mechanism being adapted to move along the rails, in combination, a source of current, means for supplying said current to the rail, means responsive to variations in flux around the rail for detecting flaws therein, said last-named means comprising a plurality of induction coils, a conductive casing for each of said coils, means whereby said carriage supports said casings, means whereby said casings are insulated from said carriage, and means whereby said carriage is insulated from the rail.
6. In a flaw detector mechanism for rails and the like, said mechanism being adapted to move along the rails, in combination, a source of current, means for supplying said current to the rail, means responsive to variations in flux around the rail for detecting flaws therein, said last-named means comprising an induction coil, a conductive casing therefore adapted to engage the rail, and means including insulating bearings for supporting said casing for pivotal movement in said carriage.

7. In a flaw detector mechanism for rails and the like, said mechanism being adapted to move along the rails, in combination, a source of current, means for supplying said current to the rail, means responsive to variations in flux around the rail for detecting flaws therein, said last-named means comprising an induction coil, a conductive casing therefore adapted to engage the rail, means including an arm pivoted in said carriage and connected to said casing for supporting said casing in said carriage, and means for insulating said arm from said carriage.

8. In a flaw detector mechanism for rails and the like, said mechanism being adapted to move along the rails in combination, a source of current, means for supplying said current to the rail, means responsive to variations in flux around the rail for detecting flaws therein, said last-named means comprising an induction coil, a conductive casing therefore adapted to engage the rail, means including an arm pivoted in said carriage and connected to said casing for supporting said casing in said carriage, means for insulating said arm from said carriage, spring means between said carriage and said arm for pressing said casing into engagement with the rail, and means for insulating said spring means from said carriage.
